UNITED STATES PATENT OFFICE.

HARRY C. GEIST, OF WAYNESBORO, PENNSYLVANIA.

JOURNAL BOX FOR CUTTERS.

Application filed January 16, 1924. Serial No. 686,677.

To all whom it may concern:

Be it known that I, HARRY C. GEIST, a citizen of the United States, residing at Waynesboro, in the county of Franklin and State of Pennsylvania, have invented certain new and useful Improvements in Journal Boxes for Cutters, of which the following is a specification.

The present invention relates to bearings for rotary cutting tools and the like, against which considerable lateral thrust or pressure is exerted during the cutting operation. It is more particularly intended for pipe or tube cutting machines. In these machines a rotary cutter is employed, and the pipe or tube is raised against the cutter, thus creating side strain on the cutter and its carrying shaft. As a consequence the shaft bearing adjacent to the cutter becomes worn and misshapen and it is difficult to maintain the proper alinement and support of the shaft. This difficulty is overcome in the present invention, the preferred embodiment of which is disclosed in the accompanying drawings.

25 In said drawings:

Figure 1 is a side elevation of the pipe cutting machine,

Figure 2 is a front elevation of the same,

30 Figure 3 is a detail elevation on an enlarged scale of the shaft bearing box,

Figure 4 is a sectional view on the line 4-4 of Figure 3,

Figure 5 is a sectional view on the line 5-5 of Figure 4,

35 Figure 6 is a detail perspective view of the bushing, indicating the manner in which it is constructed.

In the embodiment disclosed, a support in the form of a hollow standard 7 is provided, 40 and the upper portion of one wall thereof is provided with a journal box, preferably made integral with said wall. This journal box comprises a tubular portion 8 that extends into the standard and an outstanding

45 portion comprising an outstanding tubular boss 9 and a generally semi-cylindrical lower portion 10. Overlying said semi-cylindrical portion 10 is a cooperating cap portion 11. These portions 10 and 11 are connected by 50 draft bolts 12, and interposed between them are sets of removable thin spacing strips or liners 13.

55 Fitted into the box, is a bearing bushing comprising an inner completely tubular portion 14 and an outer sectional portion comprising a lower semi-cylindrical section 15

integral with the tubular portion 14. A separable cap 16 overlies the portion 15 and normally has its longitudinal edges spaced from the opposing edges of the integral portion 15. In the preferred method of manufacturing this bushing, a tubular sleeve is employed and the section 16 is cut therefrom with portions 17 milled out to form the spaces between the sections 15 and 16. The 60 bushing when in place has its tubular portion 14 extending into the tubular portion 8 and boss 9 of the box and also in the wall of the standard 7, as will be clear by reference to Figures 3 and 5. The section 16, it 65 will be noted, is under the cap 11 of the box.

The cutter-carrying shaft 18 is journaled in the bushing and box, and has a projecting end 19, on which is fixed the rotary cutting tool or disk 20. The shaft is driven in the 70 usual manner through gearing that transmits motion from a drive shaft 21. This shaft 21 is provided with fixed and loose pulleys 22 and 23 adapted to receive a driving belt that can be shifted from one to the 75 other by a belt shifter shown at 24.

Vertically slidable on the front of the standard below the cutter 20 is a work support 25 having a stem 26 that rests upon a cam 27. This cam is carried by a rock shaft 85 28 having a treadle 29 mounted thereon. A hand lever 30, mounted on one side of the machine, has a link connection 31 with a crank arm 32, also connected to the shaft 28. Obviously therefore when the shaft 28 90 is rotated by either the hand lever 30 or the treadle 29, the work supporting member 25 will be elevated, and if a pipe is thereon, said pipe will be carried into contact with the rotary cutter 20. It will be clear, that 95 this pressure places material lateral or upward strain upon the cutter 20 and the shaft 18 carrying it. Consequently the bearing of said shaft adjacent to the cutter is subjected to material wear. With the 100 present construction, it will be evident that this wear can easily be taken up by removing one or more of each set of spacing strips or liners 13, so that the alignment and proper bearing of the shaft 18 can be easily maintained. Moreover when the bushing section 16 becomes greatly worn, it can be removed and replaced by a new section 105 without the necessity of revising the entire bearing.

110 From the foregoing, it is thought that the construction, operation and many advan-

tages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new and desire to secure by Letters Patent, is:—

1. A lateral thrust bearing for rotary cutters and the like comprising a support having a contractile bearing box, a bushing comprising a portion that is transversely continuous and a portion composed of sections that is in the contractile box, and a shaft journaled in the bushing.
2. A lateral thrust bearing for rotary cutters and the like comprising a support having a bearing box, said bearing box having sections, means for drawing the sections towards each other, detachable spacing elements located between said sections, and a bushing comprising a sleeve, a portion of which is continuous, another portion comprising sections located between the sections of the box.
3. A lateral thrust bearing for rotary cutters and the like comprising a support having a bearing box, a portion of which

is continuously tubular and a portion of which comprises sections, means for drawing the sections towards each other, detachable spacing elements located between said sections, a bushing comprising a continuous sleeve fitted in the completely tubular portion of the box, said bushing having a portion comprising sections that are located between the sections of the box, and means for drawing together the box sections.

4. In apparatus of the character set forth, the combination with a supporting standard having a journal box, a portion of which is in the standard and a portion of which projects therefrom, said projecting portion comprising a lower section and an upper removable section, detachable spacing elements between the sections, draft bolts connecting the sections, a bushing comprising a tubular portion in the portion of the journal box that is located in the standard, said bushing having outer sections located between the projecting box sections, a shaft journaled in the bushing and carrying a rotary cutter at the outer end of the journal box, and an upwardly movable work support below the cutter.

In testimony whereof, I affix my signature.

HARRY C. GEIST.
